United States Patent Office

Des. 224,281
Patented July 18, 1972

224,281

HELMET

Victor J. Padilla, 13212 Magnolia,
Garden Grove, Calif. 92644

Filed Dec. 4, 1970, Ser. No. 26,293

Term of patent 14 years

Int. Cl. D2—03

U.S. Cl. D2—232

FIG. 1 is a side elevational view of a helmet showing my new design, the side opposite being a mirror image thereof;

FIG. 2 is a front elevational view; and

FIG. 3 is a top plan view.

I claim:

The ornamental design for a helmet, as shown and described.
